Primary Examiner — Paula Allen Greene(57) **CLAIM**

The ornamental design for an earphone, as shown and described.

DESCRIPTION

FIG. 1 is a perspective view of an earphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the earphone where the earphone is received in a charging case.

The broken lines immediately adjacent the shaded areas represent the bounds of the claimed design. The broken lines to the earphone case depicts unclaimed environment; all broken lines form no part of the claimed design.
